UNITED STATES PATENT OFFICE.

CROSBY FIELD, OF BROOKLYN, NEW YORK, ASSIGNOR TO BRILLO MANUFACTURING COMPANY, INC., A CORPORATION OF NEW YORK.

CLEANING DEVICE.

Application filed October 8, 1925. Serial No. 61,188.

My present invention is in the nature of a package of soap in flake or fragment form and includes a metallic fabric wrapper or bag of sufficiently fine mesh or comprising a sufficient number of layers to effectively retain the soap flakes or fragments while at the same time being freely penetrable by water. Such a package affords a means for soaping or sudsing with water, in which the material 10 of the container cannot absorb grease or dirt and is easily freed from any coatings that stick to the metal surfaces. The device is particularly adapted for the sudsing operations such as soap flakes are commonly used 15 for, for the further reason that it permits free access of water to the soap and rubbing of the soap particles to facilitate solution thereof, and also because it affords a means for instant withdrawal of the soap chips for 20 future use as soon as the water has become sufficiently soaped.

The above and other features of my invention will be more evident from the following description in connection with the accompanying drawings, in which

Fig. 1 is a face view of chips of soap with the knitted ribbon bag, illustrating one form of the invention, layers of the fabric being broken away to show the chips of soap;

30 Fig. 2 is a detail section on the line 2—2, Fig. 1; and

Fig. 3 is an enlarged view showing one form of metal ribbon fabric that may be used.

35 As shown in the drawings, a desired quantity of soap chips, 1, is enclosed in fabric, 2, which is preferably of fine mesh and preferably in two or more layers so that ordinary soap chips and even small fragments of chips 40 will be retained.

The envelope or container is preferably a very flexible metal fabric to facilitate its use for the above purposes and the fabric is preferably of such a type that it can be applied 45 for uses analogous to those of a soap-containing wash cloth and preferably the fabric is such that it affords a certain amount of scraping and scrubbing action without danger of scoring or scarring the surfaces of aluminum utensils and other metal surfaces on 50 which it may be used.

I prefer to use a relatively fine mesh fabric of flexible metal ribbons preferably of non-ferrous relatively soft metals or alloys such 55 as copper, aluminum or German silver. A

desirable metal is an alloy much like that employed in ordinary tinsel.

It is evident that metal ribbons bent in the 60 slideable loops required for stocking-knit fabric afford natural scraping edges that are not too harsh, combined with any desired size of mesh for retaining the soap flakes and for 65 scrubbing the surfaces to be cleaned. The width of the ribbon may be, say, eight to twelve times its thickness and, say, 1/16 to 1/64 inch wide by, say, 1/500 to 1/100 inch thick.

The metal fabric envelope may be in the 70 form of a container filled with the soap flakes and fastened in any desired way. A cheap way is to have the fabric made from thin flexible copper or tinsel-like ribbons made by 75 knitting on a stocking knitting machine in tubular form. When made in this form, one end may be tied, then the soap flakes inserted 75 and the other end of the tube closed and secured by wire or other suitable fastening means.

Such a container or bag has a large part of 80 its chip-enclosing sides comprised of scraping ribbon which is freely penetrable by the water while the puckered portion where either end is tied affords so many thicknesses 85 of ribbon fabric that it forms a soft cushion or handle to be grasped by the user, or it 85 may be used as a deep elastic pad for application to the surface to be cleaned.

Referring to the drawings, the fabric is in 90 two layers, 2, 2^a, while the fabric is in the form of a tube of diameter and length suitable for making an approximately spherical package. The soap chips are slipped into the tube and the free ends, 2^x, 2^x, are secured by 95 wire or other suitable bond, 3.

Where there are multiple layers, they may 95 be formed by telescoping two or more separate pieces of the fabric or by telescoping back and forth successive portions of a single length. It will be evident, however, that 100 while the tubular form is convenient, there are many other ways in which the fabric may be formed in bags suitable for retaining the soap chips.

The fabric used for the wrapper may be 105 wire of any desired cross-section and the weave or knit of the fabric may be as indicated in Fig. 3. Here it consists of ribbons interengaged longitudinally of the fabric in slip loops. The ribbon loops may assume 110 an infinite variety of positions under dif-

ferent tensions and pressures, in the different parts of the fabric, by reason of the loop structure in combination with the springiness and ribbon shape of the metal. A characteristic relation shown in Fig. 3 is where the fabric is moderately stretched so that the elastic stiffness of the ribbon loops has an opportunity to permit the ribbons to assume a characteristic position more or less edgewise to the surface. This is of advantage for several reasons. It tends to present the scraping edges of the ribbon edgewise to the surface of the fabric and consequently in the best possible position for scraping the surface to be cleaned. This also provides openings for flow of water through the fabric, directly to and from the soap at the sides. By proper manipulation, the fabric may be caused to have a variable rubbing action on the surface of the soap. For instance, when the device is used merely for sudsing water, rubbing the surface of the fabric by the hand or squeezing the bag will promote a very rapid solution of the soap and water.

If the metal ribbons of the fabric are of as soft metal and as thin as may be desirable for properly scouring metal surfaces without scratching them, rough usage of the device may wear out the fabric before the soap has been used up. If this happens in the case of the multiple layer wrapper, the only result is to expose successive layers of fabric each of which has been up to that time pro-

tected from injury by the layer that has become worn out. The novelty and advantage of this feature of my invention will be readily appreciated. The number of layers of fabric may be designed with reference to the strength of the ribbons employed in the fabric and with reference to the quantity of soap chips, for the purpose and with the result that the wrapper will last as long as the soap. It is obvious that where the package is used only for sudsing water, it will last a long time, and may be refilled with soap chips by the user, as often as may be necessary.

I claim:—

1. A cleaning device, comprising an open ended tube of abrasive metal fabric, a detergent therein, and means closing the open ends of said tube to secure the detergent within the tube, said means being spaced from said ends to provide tufts of abrasive metal fabric.
2. In a cleaning device, an open ended tube comprising a plurality of layers of abrasive metal fabric, soap chips therein, and means closing the open ends of said tube to secure the soap chips within the tube, said means being spaced from said ends to provide tufts of abrasive metal fabric.

Signed at New York, in the county of New York, and State of New York, this 7th day of October, A. D. 1925.

CROSBY FIELD.
